UNITED STATES PATENT OFFICE.

ARTHUR W. HUTCHINS, OF CRANSTON, RHODE ISLAND.

SAFETY-PIN.

1,067,922.

Specification of Letters Patent. Patented July 22, 1913.

Application filed February 18, 1911. Serial No. 609,359.

To all whom it may concern:

Be it known that I, ARTHUR W. HUTCHINS, a citizen of the United States, residing at Cranston, in the county of Providence and State of Rhode Island, have invented 5 certain new and useful Improvements in Safety-Pins, of which the following is a specification.

My present invention relates to a novel 10 improvement in safety-pins, so-called, and it consists essentially in providing the keeper-carrying base arm, as it may be termed, with a central post member disposed at substantially right angles there- 15 with, the post being constructed so as to extend to and engage the usual movable resilient puncturing member or pin-arm proper when the latter is in the clasped position. Safety-pins of this general char- 20 acter are usually formed from a single piece of suitable wire possessing a degree of elasticity and resiliency. Sometimes, however, the keeper portion, and also the eye or joint part, are formed of sheet metal. I 25 prefer to produce my improved safety-pin complete or integral from a length of wire.

An objection or disadvantage to the use 30 of former safety-pins is that, when in use, they are longitudinally slidable or movable in the material or fabric to which they are pinned. That is to say, the pins are un- 35 provided with means for positively main- taining them in position against endwise movement. When such former safety-pins 40 are employed for securing cloths, bands, or other articles of underwear or apparel to infants or young children, the pins, as thus worn, are very liable to become loosened (while clasped) or disarranged to a consid- 45 erable extent so that portions of the pin itself, even though the pin-point be pro- tected, will engage the tender skin of the wearer and produce irritation, if not abra- sion of the flesh, before the cause is dis- covered.

The object I have in view is to produce 50 a safety-pin devoid of the objectionable fea- tures referred to, the pin at the same time over-coming other disadvantages inherent in 55 safety-pins as heretofore devised. In my improved safety-pin the construction is such that when in service it is held securely in position against endwise or sliding move- ment. The manufacturing cost of the im- proved safety-pin is substantially the same as the old or unimproved safety-pin.

In the accompanying sheet of drawings, Figure 1 represents a side elevation of a safety-pin embodying my improvement; the pin being in the closed or clasped position, 60 as in use; and Fig. 2 is a transverse sectional view of the same, taken on line 2 2 of Fig. 1, the fabric being omitted.

Safety-pins of this general class are usually formed from suitable bendable wire 65 stock.

In the drawing, A designates my im- proved safety-pin complete, and as pro- 70 duced from a single piece of wire. The article comprises a base arm member a having one end bent to form a keeper or catch c, and having the other or opposite end portion bent to form a spring eye d termi- 75 nating in the longitudinally extending, sharpened, resilient pin-arm p, arranged to engage said catch. The invention herewith resides in twisting or suitably bending the wire or stock so as to produce in the base- 80 arm a about midway of its length a short post or support b disposed at right angles to the latter and located in substantially the same vertical plane. The outer or free end portion of the post part is extended trans- versely (Fig. 2) and forms a short arm or bridge b¹, the center part of which is de- 85 pressed or concave and constitutes a guide or self-centering seat b² for the adjacent part of the pin-arm p when the pin is in the normally clasped position. In fact, the re- 90 lation of the seat part to the member p is such that in order to cause the engagement of the latter with the keeper or catch, as in clasping it, the pin member p will first contact with the seat before it can be sprung inward or downward into the keeper; the 95 resiliency of the pin, in coöperation with the post, operating to prevent accidental un- clasping. When the safety-pin is in normal use, the pin-arm extends through the fabric or material, substantially as indicated at 100 f, Fig. 1, the fabric also at the same time being clamped in position between the seat b² and pin-arm, thereby positively prevent- 105 ing the safety-pin from sliding endwise in the material, or the latter from moving with relation to the pin.

I claim as my invention:—

In a safety-pin integrally formed from a single piece of wire, the combination of the base-arm having one end thereof bent 110 to form a catch member, the other end bent to form a coil spring, a substantially

straight pin-arm member extending from said coil and disposed in the same plane with that of the base-arm having its free end pointed and adapted to engage said catch, a strut member located intermediate the two ends of the base-arm and extending at right angles therefrom in the same plane with the base and pin arms, said strut formed by bending a portion of the wire of the base-arm to produce two connected strands twisted together, and having the

outer or free end of the strut further bent to form a depressed open seat disposed transversely of the base, for the purpose set forth.

In testimony whereof I have affixed my signature in presence of two witnesses.

ARTHUR W. HUTCHINS.
